UNITED STATES PATENT OFFICE

JOHN A. AMOS, OF CHICAGO, ILLINOIS, ASSIGNOR TO THE PYLE-NATIONAL COMPANY,
OF CHICAGO, ILLINOIS, A CORPORATION OF NEW JERSEY

ELECTRIC SWITCH

Application filed August 9, 1928. Serial No. 128,112.

My invention relates to improvements in electric switches particularly for use in connection with electric lighting systems of a locomotive and has for one object to provide a new and improved form of switch which combines the dimmer element and control means for the headlight and the control means for the running and cab lights in a single unitary housing. Another object of my invention is to provide a switch arrangement and switch housing which will be fool-proof and durable and of such strength as to stand up under railroad service. Other objects of my invention will appear from time to time throughout the specification and claims.

My invention is illustrated more or less diagrammatically in the accompanying drawings, wherein—

- 20 Figure 1 is a plan view;
- Figure 2 is a plan view with parts omitted and parts broken away;
- Figure 3 is a side elevation with parts in section and parts broken away;
- 25 Figure 4 is a section along the line 4—4 of Figure 1;
- Figure 5 is a section with parts omitted and parts broken away along the line 5—5 of Figure 2;
- 30 Figure 6 is a plan view of the headlight switch contact elements;
- Figure 7 is a perspective view showing the headlight contact elements and control means;
- 35 Figure 8 is a perspective view of the cab light switch block.

Like parts are indicated by like characters throughout the specification and drawings.

A is the base or housing adapted to be held in place by bolts not shown, through the bolt holes A¹ at any suitable point in the locomotive cab. It may be supported vertically or horizontally as the case may be. A² are conduits leading into the housing adapted to contain conductor wires A³ A⁴ leading from the generator. A⁵ is a conduit communicating with the housing adapted to contain conductor wires A⁶ A⁷ leading to the headlight and to the cab lights. A⁸ is the resistance unit provided with legs A⁹ adapted to be bolted to

the housing A. A¹⁰ is a cover for the housing adapted to be held in place by the screws A¹¹. B is a boss in the cover A¹⁰ adapted to provide a bearing for the switch pin B¹ which pin has a switch fork B² terminating in driving fingers B³ B⁴ located inside the housing. The end of the pin B¹ projects outwardly beyond the boss B to engage the handle B⁴ being held against rotation thereon by means of the pin B⁵ which passes through the handle head and the pin and holds the pin and switch handle in position on the cover. B⁶ is a quadrant recessed on the face of the cover. A plurality of semi-circular notches or counter sunk pockets B⁷ B⁸ B⁹ terminate in bosses B¹⁰. A lock plunger B¹¹ is slidable in the handle piece B¹² and pressed outwardly against the quadrant by the spring B¹³. When the pin engages the pocket B⁸ as shown in Figure 1, the headlight switch is off. When it has swung to the left and engages the pocket B⁷, the headlight switch is on. When it is swung to the right engaging the pocket B⁹ the headlight switch is in the dim position.

C is an insulating block fastened in the housing by means of the screws C¹. C² is a conductor piece bolted to the block C. It has a binding post C³ at which terminates the cable A³. It also has an arm C⁴ extending to the center of the block C and carrying the pin C⁵ on which is rotatably mounted the switch member C⁶. This switch member comprises two opposed plates located one on either side of a filler block C⁷ held yieldingly together by a spring C⁸ surrounding the pin C⁵ and held under tension by the cotter pin C¹⁰. These switch plates C⁶ have at opposed sides spaced spring fingers C¹¹ C¹² C¹³ C¹⁴.

Mounted on the insulating block C is a dimmer contact D adapted when the parts are in the position shown in dotted lines at the left hand side of Figure 2 to be gripped between the members C¹¹ C¹² and to close a circuit through the cable A³, binding post C³, pin C⁵, finger C¹¹ C¹², contact member D, conductor D¹, binding post D², conductor D³ to the resistance unit A⁸. Under these conditions a current leads from the other bolt through a resistance unit A⁸, conductor D⁴,

binding post D⁵, conductor D⁶, binding post D⁷ through the conductor A⁶ to the headlight, thus reducing the current and giving a dim light. When on the other hand the parts are 5 in the position shown in dot-and-dash lines in Figure 2, the blade C¹³ is in contact with the terminal member D⁸ associated with the binding post D⁷ and in this case current leads from A³, through C³, C⁶, C⁶, the finger C¹³, the member D⁸ direct to the conductor A⁶ and the 10 full current pressure is supplied to the light thus short circuiting the resistance element. When the parts are in the position shown in Figure 6, however, both the terminals D and 15 D⁸ are idle and the light is turned completely off.

E is a driving plate concentric with the plate C⁶, spaced thereabove by means of holding pins E¹ E¹. This plate has a pair of diametrically opposed apertures E² E² adapted 20 to engage the prongs or forks B³ B³ so that rotation of the hand switch causes rotation of the switch members.

Referring now to the cab light switch, the 25 conductor A⁴ comes into the housing to the binding post F. The conductor A⁷ leads out through the housing from the binding post F¹. F² F² are springs associated with said binding posts extending inwardly toward 30 one another. F⁴ is a slidably mounted contact block adapted when pushed forward to the dotted line position in Figure 2 to engage both springs and when drawn to full line position, it will be noted that these springs 35 are bent well back so as to be fully out of contact with the block F⁴. This block has a conducting surface F⁵ adapted to engage these spring fingers F² and the body thereof is of insulating material as indicated at F⁶. This 40 block slides on an insulating block F⁷ traveling between the guides F⁸ and has on its surface an upwardly bent lug strip F⁹ adapted to engage the upwardly bent portion of a spring F¹⁰, which spring serves to hold the 45 block either in or out of contact.

G is a switch handle slideable in a boss G¹ in the housing having a pin G² extending through the block F⁴. Springs G³ G³ are interposed between this rod and this block so as 50 to provide a flexible driving connection to insure that the operator will not move the block too far in either direction if he hits the handle G too hard.

The resistance element A⁸ is removably 55 mounted on the brackets A⁹ by means of the screws H which may be released to permit the exchange of the element. The binding posts D² D⁵ located as they are outside of the housing being associated with the conductors D³ 60 D⁴ make it possible to remove and replace the resistance element without opening the housing and therefore without permitting dirt, dust and moisture to get in. The housing itself is closed by means of the packing member 65 H¹ engaging the upper edge of the housing

wall and contained between the outer rib H² and the inner rib H³ on the cover A¹⁰.

I claim:

1. A switch assembly comprising a relatively flat housing, switches contained therein, a rotary switch operating handle projecting outwardly through the flat face of the housing and rotatable in a plane parallel therewith, a push switch handle projecting longitudinally through one of the sides of the housing and reciprocable in a plane parallel with the flat face of the housing and out of line with the rotatable handle, and a removable self-contained resistance unit mounted on the side of the housing opposed to the push switch handle.

2. A switch assembly comprising a relatively flat housing, switches contained therein, a rotary switch operating handle projecting outwardly through the flat face of the housing and rotatable in a plane parallel therewith, a push switch handle projecting longitudinally through one of the sides of the housing and reciprocable in a plane parallel with the flat face of the housing and out of line with the rotatable handle, and a removable self-contained resistance unit mounted on the side of the housing opposed to the push switch handle, the axis of the resistance unit being generally in the same plane as that face of the housing through which the rotatable switch projects.

3. A switch assembly comprising a generally flat housing, a pocket extending laterally from and of smaller area than the housing both of them being open on one side and a removable closure for them, sleeves integral with and projecting from opposed sides of the housing and adjacent that side furthest from the pocket, flanges integral with the sleeve and housing and in line with the bottom of the housing, brackets removably mounted on the flanges extending in a direction away from the pocket, a cylindrical self-contained resistance unit socketed at its end in said brackets.

4. A switch assembly comprising a generally flat housing, a pocket extending laterally from and of smaller area than the housing, both of them being open on one side and removable closure for them, sleeves integral with and projecting from opposed sides of the housing and adjacent that side furthest from the pocket, flanges integral with the sleeve and housing and in line with the bottom of the housing, brackets removably mounted on the flanges extending in a direction away from the pocket a cylindrical self-contained resistance unit socketed at its end in said brackets, the brackets being removable to release the resistance unit.

5. A switch assembly comprising a generally flat housing, a pocket extending laterally from and of smaller area than the housing, both of them being open on one side and a

removable closure for them, sleeves integral with and projecting from opposed sides of the housing and adjacent that side furthest from the pocket, flanges integral with the sleeve and housing and in line with the bottom of the housing, brackets removably mounted on the flanges extending in a direction away from the pocket, a cylindrical self-contained resistance unit socketed at its end in said brackets, a rotatable switch handle 5 projecting through the removable closure and adapted to rotate in a plane parallel therewith, a push switch handle projecting longitudinally through that side of the pocket furthest removed from the housing adapted to reciprocate in a plane parallel with the closure but on the opposed side from it with respect to the rotatable switch.

10 Signed at Chicago, county of Cook and State of Illinois, this 5th day of August, 1926.

15 20 JOHN A. AMOS.
